(57) **CLAIM**

The ornamental design for a surface configuration of an instrument display panel for a vehicle, as shown and described.

DESCRIPTION

This application is related to the following co-pending applications, of the inventors, filed on even date herewith and entitled Surface Configuration of an Instrument Display for a Vehicle: Application Ser. No. 29/189,225; Application Ser. No. 29/189,256; and Application Ser. No. 29/189,176. FIG. 1 is a front view of a surface configuration of an instrument display panel for a vehicle according to our novel design;

FIG. 2 is a bottom view of the surface configuration of an instrument display panel for a vehicle according to our novel design;

FIG. 3 is a right perspective view of the surface configuration of an instrument display panel for a vehicle according to our novel design; and,

FIG. 4 is a left perspective view of the surface configuration of an instrument display panel for a vehicle according to our novel design.

The broken lines are for illustrative purposes only and form no part of the claimed design.
